UNITED STATES PATENT OFFICE.

WILLIAM B. FENN, OF COLUMBUS, OHIO, ASSIGNOR TO THE WEDOIT COMPANY, OF COLUMBUS, OHIO, A CORPORATION OF OHIO.

LIQUID-STERILIZING DEVICE.

1,292,742.

Specification of Letters Patent. Patented Jan. 28, 1919.

Application filed June 16, 1913. Serial No. 773,908.

To all whom it may concern:

Be it known that I, WILLIAM B. FENN, a citizen of the United States, residing at Columbus, in the county of Franklin and State 5 of Ohio, have invented a certain new and useful Improvement in Liquid-Sterilizing Devices, of which the following is a specification.

The particular object of this invention is 10 to provide means whereby a fluid can be quickly, thoroughly and economically sterilized. In the sterilizing or cooking of canned goods a modicum of an aqueous solution of salt or sugar is oftentimes added.

15 My invention is particularly adapted to sterilize such a solution and prepare it for introduction into the goods to be canned. My invention is also adapted for sterilizing soups or other liquids.

20 The invention is embodied in the construction herein shown and described and then particularly pointed out in the claims.

In the accompanying drawings illustrating one example of the invention—

25 Figure 1 is a central vertical section of the sterilizing device.

Fig. 2 is a plan view of the upper end of the device as shown in Fig. 1.

Fig. 3 is a horizontal section on the line 30 $\alpha-\alpha$ Fig. 1.

Fig. 4 is a view in elevation showing the device on a smaller scale in connection with a pump and other appurtenances.

In the views 5 designates a casing forming 35 a chamber 6. This casing consists of a tube like body having its ends formed to receive a wrench and internally threaded for the connection of other parts.

7 designates a tube closed at one end with 40 a plug 8 secured by a pin 9. The tube 7 is threaded at 10 to be connected with the lower end of the casing 5 the part extending into the casing being provided with numerous small perforations 11. Within the tube 45 7 is another tube 12 also plugged at its upper end and provided with numerous small perforations 13. The perforated ends of the tube 7 and 12 are adjacent to each other within the chamber of the casing 5. The

50 tubes 7 and 12 are connected by a T-connection 14 which is threaded at one end directly onto the lower end of the tube 7 and at the other end onto the exterior of the tube 12 by suitable reducing thimbles 15 and 16 said 55 thimbles closing the opening between the

connection and the tube 12. The lateral threaded opening 14^a of the T-connection receives a pipe 20 for the introduction of steam under pressure as hereinafter explained. The flow of steam through the 60 pipe 20 is controlled by an ordinary valve, the handle of which is indicated at 21 (see Fig. 4).

The lower end of the tube 12 is connected with a suitable pump 17 the connecting 65 member 18 containing an ordinary valve for controlling the flow from the pump into the tube 12. The said valve is operated by the usual handle as seen at 19.

The upper end of the casing 5 has connected to it a pipe or conductor with suitable elbows if convenient leading to the place where it is desired the discharge shall be made. Said pipe also contains an ordinary valve as seen at 22 for controlling or 70 regulating the flow of liquid through it and a valve 23 for stopping the discharge when desired.

In practice the solution or material to be sterilized or cooked is forced into the tube 80 12 by means of the pump at a pressure of, say, forty pounds while the steam is admitted to the tube 7 from a suitable boiler at a pressure of, say, fifty pounds. The liquid in the tube 12 is sprayed into the space between the latter and the tube 7. Being thus sprayed the steam admitted between the tubes commingles with and thoroughly and quickly heats the liquid and the two bodies thus pass out through the perforations of 85 the tube 7 to the place of discharge. The pressure at which the liquid to be treated is forced through the pipe 7 and the pressure of the treating steam through the pipe 12 may be varied and regulated but it is ad- 90 vantageous, I have found, that the pressure of the treating steam be somewhat in excess of the pressure of the treated material because, as I believe, of the rapid condensation of the steam in the operation.

100

What I claim is:

1. Apparatus for sterilizing liquid comprising means for continuously flowing liquid under pressure through a passage, means for breaking up such liquid *en route*, 105 means for applying steam to such liquid while it is broken up, and means for regulating the discharge of the commingled liquid and steam in a manner to maintain intimate application of the steam to the broken- 110

up liquid without interrupting the continuous flow of the liquid.

2. Apparatus for sterilizing liquids comprising means for forcing the liquid under pressure through a reticulate plate into a chamber, means for delivering steam under pressure to such chamber, a wall for said chamber of reticulate material through which the commingled liquid and steam 10 pass, and a regulable discharge outlet for the commingled liquid and steam to vary the intimacy of contact of the liquid particles and the steam.

3. Apparatus for sterilizing liquids comprising means for flowing such liquid under

pressure through a perforated tube, means for introducing steam under pressure about said tube, perforated means for permitting passage of the commingled steam and liquid, and means for permitting the discharge 20 of said commingled fluids, said means having a regulated opening to maintain the commingled fluid under regulated pressure and consequent temperature previous to such discharge.

WILLIAM B. FENN.
